CATCH FOR DRAWERS, DOORS, AND THE
LIKE

Fred M. Jacobson, Bellingham, Wash.

Application May 21, 1946, Serial No. 671,245

1 Claim. (Cl. 292—78)

1

The invention relates to catches for sliding drawers, doors and other moving objects to hold them yieldingly at a closed position, and particularly to a catch adapted for use on drawers and cabinet doors, but also applicable to use on other doors, slides and other moving elements.

It is a special object to present a catch of novel construction, adapted to function effectively, and which will be strong and liable in a minimum degree to deterioration by wear and hard use.

It is also an important aim to offer such a device which may be assembled with a minimum number of fastenings, and the operative parts of which may be assembled and removed without the use of special tools.

Another important object of the invention is to present a novel construction of strike or keeper for such devices. A still further aim is to give a novel construction of case for the latch. A further purpose is to disclose a novel assembly of spring pressed latch in which friction and binding action of the parts is greatly reduced.

Additional objects, advantages and features of invention reside in the construction, arrangement and combination of parts involved in the embodiment of the invention, and will be understood from the following description and accompanying drawing, in which,

Figure 1 is a side elevation of the catch and keeper installed upon a sliding drawer, a portion of cabinet being shown.

Figure 2 is a view similar to Figure 1, in section.

Figure 3 is a view similar to Figure 2 showing the catch and keeper parts engaged.

Figure 4 is a cross section on the line 4—4 of Figure 3.

Figure 5 is a vertical section on the line 5—5 of Figure 3.

Figure 6 is a vertical section on the line 6—6 of Figure 3.

Figure 7 is a fragmentary enlarged sectional view illustrating the mounting of the plunger and spring of the catch.

There is illustrated a portion of a cabinet frame 10, slidably mounting a drawer 11. The keeper 12 of my device is mounted on the base 13 of the cabinet inwardly of the rear wall 13'. It consists of a simple strip of sheet metal having a planiform shank portion 14 and a right angular extension upwardly curved to form a keeper body 15. The shank 14 is apertured to receive an attaching screw 16, the shank being secured flat against the base. Each edge of the shank is provided with a surface penetrating spur 17 which

2

are driven into the base 13, and by the use thereof, a single screw effects the mounting of the keeper.

The catch assembly consists of a case 18 formed of a single blank of sheet metal bent on parallel lines to form a planiform cover wall 19, parallel side walls 20 at right angles to the wall 19, and foot flanges 21, consisting of out-turned portions of the material at the outer edges 10 of the walls 20, these flanges being in a plane parallel to the cover wall, and being longitudinally slotted at 22 to receive fastening screws 23 by which the device is secured to the rear wall of a drawer or other structure. This mounting 15 permits relative adjustment of the catch assembly toward or away from the keeper. The outer portions of the walls 20 and the cover wall 19 are cut away as at 24, so that the side walls extend beyond the cover wall a distance. The side walls 20 are each provided with an inwardly struck ear 25, serving as a fulcrum pivot for a catch dog or lever 26. This lever is peculiarly formed for novel functions which it performs, and may be either cast, cut from block stock or stamped from thick metal, although it may be made thinner than in the specified embodiment if desired, to facilitate stamping. It is formed with an inner arm 27 and an outer arm 28, the extremities of 25 which are spaced apart slightly greater than the width of the keeper 15, the arms being extended at their extremities for a distance so that a bight space 29 is formed therebetween into which a part of the keeper 15 may be received. The pivot of the lever is located close to the base of the arm 27, so that for a given movement of the lever, the arm 28 moves a much greater distance than the arm 27. The pivoting of the lever on the ears 25 is attained by forming a notch or slot 30 in the inner edge of the lever close to the base of the arm 27, the lever being adjusted with the arm 27 projecting under the ears and then pressed forwardly until the ears seat in the slot, which is suitably rounded at its root portion to afford a proper bearing on the ears. The lever is formed with a rearwardly extended portion 32, which is equivalent to a third arm, and this is formed with a notch 33 transversely therein at its extremity, in which there is rested the outer transverse bar portion 34 of a spring guide and plunger 35, formed of sheet metal. This bar portion 34 is of a size to fit closely enough between the walls 20 of the case to prevent the bar portion 34 from sliding laterally out of the notch of the lever 26. The plunger 35 is extended in 35 close parallel relation slidably through an aper-

ture 36 in the rear wall 37 of the case. The aperture 36 is formed by stamping the metal inwardly to provide a short sleeve 39. Seated around the sleeve 39 and engaged upon the plunger 35 and resting against the bar 34, a helical spring 40 is confined, holding the plunger at all times pressed against the lever 26, so as to hold the latter in either of the two alternate positions. By this construction it will be seen that the spring is held spaced so as to not contact the plunger 35, thereby reducing friction and affording free sliding movement of the latter.

It will be noted that the notch 33 will move with the lever to a distance on either side of a line from the aperture 36 in the wall 37 to the ears 25, so that the spring swings beyond dead center in movement of the lever 26 to either limit, and so will hold the lever yieldingly in either position. Movement of the lever to released position is limited by engagement of the heel 38 with the transverse bar 34, while its movement in the opposite direction will be checked by engagement with the keeper 15 when the drawer is closed. It will be seen that the arm 28 does not contact the case wall 19, and that the spring 40 absorbs all shock incident to such movement of the catch.

The latch device being in normal open position, as shown in Figure 1, when the drawer is moved to closed position, the arm 28 will be retracted, and will clear the keeper 15, but the arm 27 will be projected so as to be engaged by the keeper 15, and when so engaged will be swung inward thereby, so as to cause arm 28 to swing rearward to present the bight 29 over the keeper 15. The initial portion of this movement will be directly accomplished by pressure of the keeper 15 against the arm 27, but as soon as the spring and plunger have passed dead center relation to the lever 26, further movement of the lever will be effected by action of the spring 40. With the arm 28 thus engaged with the keeper, the drawer will be held against accidental opening and held it until some force is applied to the drawer sufficiently to overcome the pressure of the spring 40 and force the arm 28 upwardly so as to clear the keeper 15, the arm 27 being moved downwardly so that it will strike the keeper 15 on the next full closing movement of the drawer.

The catch and keeper have been described as applied to a drawer and cabinet structure, but it will be apparent that the device may be applied to various types of doors or other closures where a quick release and latching of the closures is desired; and while the device has been specifically shown and described, I do not regard the invention as limited to the exact construction and ar-

rangement, and various modifications thereof may be made without departing from the spirit of the invention.

I claim:

- 5 A new article of manufacture, a latch comprising an elongated metal case having an open end, consisting of parallel side walls, a front cover wall and a top wall, each of said side walls having a right angularly extended flange, each flange being provided with a longitudinal slot for reception of respective fastening means, said side walls further having an inwardly struck ear adjacent the open lower end of the case, said top wall having an inwardly directed open sleeve, a lever pivotally mounted on said ears, said lever having a short arm normally projecting downwardly from the open lower end of the case and a long arm in fixed relation thereto projected forwardly, the short arm adapted to engage a keeper under closing movement of the latch, the long arm initially clearing the keeper but engageable therewith upon movement of the short arm by engagement of the latter with the keeper, said lever further having a notch rearwardly of said 20 long arm, a plunger engaged in and projecting through said sleeve, said plunger having a transverse bar disposed within said notch, a helical spring on said plunger, one end of said spring being seated around said sleeve, and the other end thereof being in bearing engagement with said transverse bar to hold the lever yieldingly for movement in opposite directions, and the cover wall of said case stopping short of the extreme forward position of the long arm of the 25 lever to prevent contact between the cover wall and the long arm, whereby said spring absorbs the shock incident to such movement of the catch.
